UNITED STATES PATENT OFFICE.

FERDINAND ZIGANEK AND FRANK W. WILKINSON, OF WEST TOLEDO, OHIO.

ADJUSTABLE STRIKE-PLATE.

1,111,425.

Specification of Letters Patent. Patented Sept. 22, 1914.

Application filed June 8, 1914. Serial No. 843,826.

To all whom it may concern:

Be it known that we, FERDINAND ZIGANEK and FRANK W. WILKINSON, citizens of the United States, residing at West Toledo, in the county of Lucas and State of Ohio, have invented certain new and useful Improvements in Adjustable Strike-Plates, of which the following is a specification, reference being had to the accompanying drawings.

This invention relates to new and useful improvements in strike plates for connection to door frames, to receive the bolts of latches connected to swinging doors.

An object of this invention is the provision of a strike plate which is adjustable, so as to compensate for the space between the frame of the door and the outer edge of the door, whereby the strike plate may be adjusted to receive the bolt of the latch so that the door will be securely held when in closed position.

A further object of this invention is the provision of a strike plate which is provided with an adjustable latch receiving member, the latch receiving member comprising a base plate which is provided on opposite sides with outwardly extending flanges, the flanges projecting through an opening in the strike plate, means being provided to adjust the latch receiving member so that the free edges of the flanges may be moved to extend any desired distance outwardly of the strike plate.

With these and other objects in view, our invention consists in the novel construction, combination, and arrangement of parts to be hereinafter more fully described, claimed, and illustrated in the accompanying drawing, in which,

Figure 1 is a front elevational view of our invention; Fig. 2 is a side elevational view thereof; Fig. 3 is a sectional view on the line 3-3 of Fig. 1; and Fig. 4 is a perspective view of the adjustable member mounted within the strike plate.

Referring more particularly to the drawing, the numeral 1 designates the strike plate of our invention, which is provided with the usual tumbler receiving slot 2 and an opening 3 to receive the latch. A plate 4 is disposed rearwardly of the opening 3 in the strike plate, the plate 4 having for-

wardly extending end walls 5 at its upper and lower edges which are connected to the upper and lower edges of the opening 3 in the strike plate, the plate 4 being of slightly less width than the width of the opening 3. A latch receiving cup is provided, the cup comprising a base wall 6 and side walls 7 projecting from the opposite side edges of the base wall, the side walls engaging the opposite side edges of the plate 4 and projecting forwardly through the opening 3 in the strike plate.

The base wall 6 of the cup is provided with a central opening 8 therethrough, and disposed through the opening is a screw 9, the inner end of which is swivelly engaged in the plate 4. Threadably mounted upon the screw and disposed between the head thereof and the outer face of the base 6, is a nut 10, and it will be seen that when the screw is turned to move the nut outwardly upon the screw, the nut engaging the base of the cup moves the same outwardly so that the outer edges of the walls 7 of the cup are advanced beyond the outer face of the strike plate 1. To prevent the nut 10 from turning when the bolt 9 is rotated, a loop 11 is formed on the base 6 of the cup to extend over the nut. Laterally directed flanges 12 are formed on the upper and lower edges of the base 6 of the cup, the flanges being formed with outwardly extending lugs 13 and similar lugs 14 are formed on the inner face of the strike plate 1, the lugs 13 and 14 receiving the opposite ends of expansion helical springs 15 by means of which the cup is normally held in its innermost position. The forward extremity of one of the walls 7 of the cup is provided with a laterally projected flange 16, the outer face of which is beveled, the extremity of the flange 16 being directed rearwardly as at 17, through a slot 18 in the strike plate, the beveled flange 16 serving as a guide to move the latch inwardly so that the same may readily drop into the cup to hold the door in closed position. The portion 16 also serves as a stop to limit the inward movement of the cup in the strike plate so that the forward edges of the side walls of the cup always project outwardly of the forward face of the strike plate.

In the practical use of our device, the strike plate carrying the cup is inserted in the door frame in the usual manner, with the beveled portion 16 of the wall of the cup 5 facing in the direction of the door when in open position so that when the door is closed, the latch will ride over the beveled portion 16 and drop into the cup to hold the door in its closed position. Should the strike 10 plate be connected to a door frame in which the inner edge of the door when closed is spaced from the frame to such a degree that the latch carried by the door will not engage the strike plate, the screw 9 may be 15 rotated to advance the nut 10 forwardly on the screw which moves the cup forwardly, whereby to dispose the outer edges of the side walls 7 of the cup forwardly of the outer face of the strike plate to the desired 20 distance, so that the latch will strike the beveled portion 16 and drop into the cup. It will be seen that the springs 15 normally maintain the cup in its innermost position against the nut 10, so that when the latch 25 strikes the beveled portion 16, the cup will not be caused to rebound from the nut, owing to the jar interposed upon the cup.

Having thus fully described our invention, what we desire to claim and secure by 30 Letters Patent, is:—

1. A device of the class described comprising a strike plate having a latch receiving opening therein, a latch receiving cup carried by the strike plate, said cup comprising 35 a base wall and forwardly extending side walls projecting through the opening in the strike plate, a screw carried by the strike plate and projecting loosely through the base wall of the cup, a nut mounted on the 40 inner end of said screw for engagement against the inner face of the base wall of the cup, means for preventing rotation of said nut with relation to the screw, whereby upon rotation of the screw the cup may be moved 45 to dispose the free edges of its side walls at any desired distance outwardly of the strike plate, and means for normally holding the cup in its innermost position with the base wall thereof engaged against said nut.
2. A device of the class described comprising a strike plate having a latch receiving opening therein, a latch receiving cup carried by the strike plate, said cup comprising 50 a base wall and inwardly extending side walls projecting through the opening in the strike plate, means for adjusting said cup to dispose the ends of the side walls different distances outwardly of the strike plate, said strike plate having a slot formed therein to 55 one side of the latch receiving opening, the outer extremity of one of the side walls being provided with a laterally projected flange disposed in the path of the latch, and the extremity of said flange being directed 60 rearwardly for engagement in said slot, said

flange limiting the inward movement of said cup with relation to the strike plate.

3. A device of the character described comprising a strike plate having a latch receiving opening therein, a plate disposed rearwardly of the opening and having forwardly extending end walls connected to the upper and lower edges of the opening in the strike plate, said plate being of relatively less width than the width of the opening in the strike plate, a latch receiving cup comprising a base wall and forwardly extending side walls, said side walls engaging the opposite side edges of the second mentioned plate and projecting through the opening in the strike plate, and means for adjusting said cup to dispose the ends of the side walls thereof different distances outwardly of the strike plate. 70 75 80

4. A device of the class described comprising a strike plate having a latch receiving opening therein, a plate disposed rearwardly of the opening in the strike plate and having forwardly extending end walls connected to the upper and lower edges of the opening in the strike plate, the last mentioned plate being of relatively less width than the width of the opening in the strike plate, a latch receiving cup comprising a base wall having forwardly projecting side 85 90 95 walls engaging the opposite side edges of the second mentioned plate and projecting forwardly through the opening in the strike plate, an adjusting screw disposed through a central opening in said second mentioned plate, the free end of said screw being disposed through the base of said cup, and a nut mounted upon the free end of said screw for engagement against the base wall of said cup, whereby upon rotation of the screw, the cup may be moved to dispose the free edges of the side walls of the cup at any desired 100 105 distance outwardly of the strike plate.

5. A device of the class described comprising a strike plate having a latch receiving opening therein, a plate disposed rearwardly of the opening in the strike plate and having forwardly extending end walls connected to the upper and lower edges of the opening in the strike plate, the last mentioned plate being of relatively less width than the width of the opening in the strike plate, a latch receiving cup comprising a base wall having forwardly projecting side walls engaging the opposite side edges of the second mentioned plate and projecting forwardly through the opening in the strike plate, an adjusting screw disposed through a central opening in said second mentioned plate, the free end of said screw being disposed 110 115 120 125 130 through the base of said cup, a nut mounted upon the free end of said screw for engagement against the base wall of said cup, whereby upon rotation of the screw the cup may be moved to dispose the free edges of

the side walls of the cup at any desired distance outwardly of the strike plate, the base of said cup having laterally directed flanges formed on its upper and lower edges, and 5 expansion springs disposed between said flanges and said strike plate to normally hold said cup in its innermost position.

In testimony whereof we hereunto affix

our signatures in the presence of two witnesses.
